US00D764504S

(12) **United States Design Patent**
Yagisawa et al.

(10) **Patent No.:** **US D764,504 S**
(45) **Date of Patent:** **** Aug. 23, 2016**

(54) **VEHICLE DISPLAY UNIT WITH GRAPHICAL USER INTERFACE**

(71) Applicant: **MITSUBISHI ELECTRIC CORPORATION**, Tokyo (JP)

(72) Inventors: **Takaki Yagisawa**, Tokyo (JP); **Hideo Imanaka**, Tokyo (JP); **Masami Aikawa**, Tokyo (JP)

(73) Assignee: **MITSUBISHI ELECTRIC CORPORATION**, Tokyo (JP)

(**) Term: **14 Years**

(21) Appl. No.: **29/490,610**

(22) Filed: **May 12, 2014**

(30) **Foreign Application Priority Data**

Nov. 18, 2013 (JP) 2013-026949

(51) LOC (10) Cl. **14-04**

(52) U.S. Cl.

USPC **D14/486**; D14/487

(58) **Field of Classification Search**

USPC D14/485-495

(57) **CLAIM**

The ornamental design for an vehicle display unit with graphical user interface, as shown and described.

DESCRIPTION

FIG. 1 is a front elevational view of a vehicle display unit with graphical user interface, showing our new design;

FIG. 2 is a top plan view thereof, a bottom plan view is a mirror image thereof; and,

FIG. 3 is a right side elevational view thereof, a left side elevational view is a mirror image thereof.

The outer peripheral broken line in FIG. 1 and all broken lines in FIGS. 2-3 represent the display screen and form part of the claimed design.

The alternate long and short dash lines of FIG. 1 show the boundary of the claimed design and form no part thereof.

1 Claim, 2 Drawing Sheets
